UNITED STATES PATENT OFFICE.

WILLARD M. FULLER, OF NEW YORK, N. Y., ASSIGNEE TO CYRUS PYLE, OF BROOKLYN, N. Y., AND DANIEL ELDRIDGE, OF NEW BRUNSWICK, N. J.

CAR-HEATER.

SPECIFICATION forming part of Letters Patent No. 274,753, dated March 27, 1883.

Application filed December 1, 1882. (No model.)

To all whom it may concern:

Be it known that I, WILLARD M. FULLER, of New York, in the county and State of New York, and a citizen of the United States, temporarily residing at Lexington, in the county of Davidson and State of North Carolina, have invented new and useful Improvements in Car-Heaters, of which the following is a specification.

10 The object of this invention is to provide a furnace for heating railroad-cars from underneath and outside of the car, and which shall be compact and readily applied to a car with but a slight change in the latter, which shall 15 be convenient, simple, and efficient in every particular, and by which, with but a slight expenditure of fuel, the car can be comfortably and constantly heated. These objects I attain by means of the devices illustrated in the 20 annexed drawings, in which—

Figure 1 represents a vertical central section of my improved heater attached to a car. Fig. 2 is a like view taken on a plane at right angles to Fig. 1. Fig. 3 is a plan view of the 25 boiler with the steam-dome in section and a portion of the boiler broken away. Fig. 4 represents the ash-pit and the grate resting in its seat. Fig. 5 is a bottom view of the ash-pit.

30 A indicates the boiler, which consists of a short cylindrical body cast with a flange, a, around its upper edge, a pair of lugs, a', extending laterally from such flanged edge, and a tubular neck, a'', which rises from the top 35 and constitutes the steam-dome of the boiler, as a safeguard from fire. To provide an increased area of heating-surface, I secure in the bottom of the boiler a set of short tubes, B, which depend from the boiler, and are closed 40 at their lower ends. These tubes may be made of any shape, size, or style. In securing this boiler in position its dome or steam-jacket is passed up through an opening in the floor of the car, and its top is held against the floor-timbers C by means of bridges or cross-bars C', which are fitted against the under side of the lugs a' and secured to the timbers. This 45 forms a simple and effective mode of securing the boiler and admits of its being readily removed when necessary.

D indicates a metal plate which is secured

to the floor at a point above the steam-jacket. This plate has an opening which registers with the upper end of the steam-dome, as illustrated in Fig. 1. A metal cap, E, which has 55 its flanged top fitted in said opening, has its body portion e fitted in a vertical pipe, F, which passes centrally through the steam-boiler and its dome, thus forming a magazine or conduit for supplying the furnace with fuel 60 from the inside of the car. The body e of this cap is made hollow and filled with plaster-of-paris or some other non-conductor of heat, whereby the exposed top of the cap will not become hot. This pipe F is secured at its 65 lower end in the bottom of the boiler and passes through the same, and, if desired, can be extended to within a short distance from the fire-grate, as shown in dotted lines, thereby forming a self-feeder or magazine for fuel. 70 The upper end of this pipe is swelled into the upper end of the dome, which has an inner annular flange, e', just below its upper edge. This flange fits the pipe F, and by being made lower than the upper edge of the dome an annular seat will be formed for a rib upon the under side of the cap. The cap can be removed from the pipe when it is desired to feed the fire in the furnace below the boiler, and when reseated will be locked flush with 75 the top of the plate D, thus presenting no obstruction along the floor. Ample steam-space is left between the walls of the dome and the pipe F, and pipe-connection is made with the steam-dome for the purpose of conveying 80 steam to the radiators, and at the same time protect wood-work from danger.

85 The furnace G is composed of three sections, the upper one, g, of which surrounds the lower portion of the boiler. This upper section of 90 the furnace-shell is flanged around its upper edge and secured to the boiler by bolts, which are passed through its flange and through the flange a of the boiler. The lower sections, g', 95 g'', of the furnace, which respectively provide the fire-box H and ash-pit I, are flanged and bolted together at their meeting edges, the section g' being also flanged at its top edge and bolted to the upper section, g. The smoke-pipe L leads from the upper section of the furnace and is conducted to any desired point.

100 K indicates the grate, which rests in an an-

nular seat formed in the lower or third section of the furnace. An arm, *h*, of this grate extends through an opening in the side of the furnace and connects with a crank end of the rod *M*, which enters a slot in the arm of the grate. This rod extends up through a bearing, *m*, cast with one of the furnace-sections, and also passes up through the flange *a* of the boiler, whereby upper and lower bearings are provided for the rod. The upper end of this rod extends in an opening in plate *D*, and can be squared so that it can be caught by some suitable shaker and operated by an attendant within the car.

15 The bottom of the ash-pit has two or more openings for the discharge of ashes. These openings are closed by a rotary damper or grate, *N*, which consists of a plate provided with suitable openings and pivoted to the under side of the furnace, which said plate can also be operated by an attendant within the car by providing an attachment or rod-connection similar to that used for the grate. The furnace is formed with an inlet or shaft passage, *O*, at its base. This passage is closed by a hinged door, *P*, which drops over the mouth of the passage by its own weight. It is proposed to cause this door to be opened automatically, and to a greater or less extent, according to the requirement of the fire. To such end I connect the tubular neck of a shell, *Q*, with the top of the boiler, and within said shell I arrange a flexible diaphragm, *q*, which connects with a lever, *R*, by means of a plunger-rod, *r*, working through the top of the shell. This plunger-rod connects with the pivoted lever *R*, which is pivoted at one end, and at its remaining end connected with a lever, *S*, by means of a link, *s*. This lower lever connects with the ash-pit door *P* by means of a chain, *s²*, or equivalent connection; hence when there is an excess of heat and steam the latter will force the diaphragm up, and, through the medium of the links, levers, and connections hereinbefore described, slacken the chains and allow the door to close, so as cut off the draft, and thereby lower the fire. It is also proposed to work a similar damper in the smoke-pipe in close connection with the one at bottom of furnace by the same device and by the same plunger and lever-connection.

As this heater will be located at or about the under side of the car, the steam-pipe will radiate out from the heater to the sides of the car.

55 *U* indicates the steam-pipes leading from the dome under the floor to the sides of the

car. Each pipe rises above the floor at the side of the car, as indicated in Fig. 2, and connects with a radiator or with the branch pipes *60* *U'*, which run to the end of the car and are then returned to the boiler. The steam entering the pipes from the dome passes through the pipes, thereby heating the same. The water of condensation is conducted back into the *65* boiler, so that there is a constant circulation through the pipes.

Having thus described my invention, what I claim is—

1. A boiler for railway-heaters, cast with a *70* shortcylindrical body, and with a tubular dome or steam-jacket which rises centrally from the top of the boiler and enters an opening in the floor of the car, and having a central tube passing down through the dome and opening into *75* the fire-box, a steam-space being left between said tube and the steam-dome throughout the entire extent of the latter, substantially as described.

2. The combination, with the boiler provided *80* with a tubular dome or steam-jacket, of the pipe *F*, secured centrally within the boiler and its dome or steam-jacket, and a cap secured upon the dome or steam-jacket and fitted to the pipe which passes through the same, said *85* cap having a hollow body filled with non-conducting material, substantially as described.

3. The combination, with the furnace, of a grate seated in an annular recess formed in the wall of the ash-pit, said grate having an *90* arm passing through an opening in the fire-box and engaging with the crank-pin of a vertical shaft having its bearings in flanges formed on the furnace and extending upward into a recess in the floor of the same.

4. A heater for cars, consisting of the boiler having closed tubes extending into the fire-box, a steam-dome rising to the floor of the car, a tube inclosed by said dome, with an intervening steam-space, said tube being provided with a suitable cap, and a grate seated in an annular recess in the wall of the ash-pit and connected with a crank-pin upon a vertical shaft, the squared end of the latter being arranged in a recess in the car-floor, substantially as described.

95 In testimony whereof I have hereunto set my hand in the presence of two subscribing witnesses.

WILLARD M. FULLER.
